(57) **CLAIM**

We claim the ornamental design for a clothing care machine with showcase, as shown and described.

DESCRIPTION

FIG. 1 is a perspective view of a clothing care machine with showcase showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof shown in a state of use. The broken lines showing a hanger and a shelf in FIG. 8 represent environmental structure and form no part of the claimed design. All other broken lines shown in the drawings depict portions of the clothing care machine with showcase and form no part of the claimed design.
